UNITED STATES PATENT OFFICE.

HAZEL BRILL, OF BROOKLYN, NEW YORK, ASSIGNOR TO BRASS GOODS M'F'G CO., OF NEW YORK, N. Y., A CORPORATION OF NEW YORK.

DESIGN FOR A CONTAINER.

56,095.

Specification for Design. Patented Aug. 17, 1920.

Application filed January 6, 1920. Serial No. 349,819. Term of patent 14 years.

To all whom it may concern:

Be it known that I, HAZEL BRILL, a citizen of the United States, residing at Brooklyn, in the county of Kings and State of New York, have invented a new, original, and ornamental Design for a Container, of which the following is a specification, reference being had to the accompanying drawings, forming part thereof, in which—

Fig. 2 is a side elevation of the same.
Fig. 3 is a vertical section taken through the container.

I claim:
The ornamental design for a container as shown.

HAZEL BRILL.
